UNITED STATES PATENT OFFICE.

CHARLES R. HARRISON, OF FOND DU LAC, WISCONSIN.

POSTAL-BAG RACK.

SPECIFICATION forming part of Letters Patent No. 292,911, dated February 5, 1881.

Application filed December 5, 1883. (No model.)

To all whom it may concern:

Be it known that I, CHARLES R. HARRISON, a citizen of the United States, residing at Fond du Lac, in the county of Fond du Lac and State of Wisconsin, have invented 5 new and useful Improvements in Postal-Bag Racks, of which the following is a specification.

I have heretofore invented and patented apparatus for distributing mail, consisting, substantially, of metallic bag-racks; and my invention now relates to improvements in these postal-bag racks, in which sections are made movable, and swung open from either side 10 thereof by means of casters in conjunction with link-hinges and shunts, and in which mortised hook-shanks operate in conjunction with pins or pegs in the rack-rods; and the objects of my improvements are, first, to provide 15 convenient passage-ways through the line of racks by detachable swinging sections; second, to relieve and turn the casters into the curved track of the swinging sections; and, third, to provide a uniform and secure 20 opening to the mouths of the bags. I attain these objects by the mechanism illustrated in the accompanying drawings, in which—

Figure 1 is a top view of the apparatus with one section swung open and another closed, 25 the dotted lines 2 2 showing the lines or tracks of movement. Fig. 2 is a ground plan of the swinging sections with its parts; Fig. 3, a section of the swinging rack. Fig. 4 is a front view of the rack-rod provided with the pins 30 or pegs and hooks; and Fig. 5, a vertical cross-section of the mortised hook, the pin, and rack-rod.

Similar letters refer to similar parts throughout the views.

The platform A supports the movable rack-section, and is mounted upon casters a a, and 40 hinged by means of slotted eyes d d with hinge-bolts e e. This hinge bolt or pin is firmly driven into or attached to the floor of the room at the outer corners of the platform or movable section A. The link or eye d is affixed to and on a plane with the platform at either outer corner thereof, and when engaged with the pin e on either corner forms a hinge, upon 45 which turns the movable rack-section, opening to the right or left, as its hinge may be

adjusted; but the casters a a, being heavily loaded, will have a tendency to a straight line in their movement forward, and must cramp, if the hinge or pivot d e be rigid in its action. 55 The casters must be guided in the curved track 2 2 required by the swing of the section. I accomplish this by means of the slotted form or ellipse of the hinge-eye d, allowing a play of the hinge-bolt e in the eye and a movement 60 of the section laterally with reference to the line 2 2, so that the pressure of the cramped casters crowds the rack-section laterally, and so moves the socket of the caster-shank (which is affixed to the bottom of the platform A) to 65 one side, thus turning and guiding the caster-wheels in the curved track. When closing the movable section, the pressure of the casters throws the platform away from the fixed rack x to the limit of the slot d, which would 70 cause the section to overlap the fixed rack at the corner or face diagonally opposite the hinge. I meet this difficulty and throw the platform back to place by means of the cam or curved block f, affixed to the platform A 75 at the outsides of the swinging section, and when closing this cam meets and slides over the block or stop g, which is affixed firmly to the floor near the outside corner of the fixed rack x. This engagement of the cam f with 80 the stop g throws the moving section back to its place when closed.

The further improvement is to prevent the hooks B slipping toward each other by reason of the jarring and increasing weight of the 85 mail-bags while being filled; and it consists of affixing to the rack-rods y at proper intervals pegs or pins C, which may be small screws with round heads passed into and through the rod on its front face, leaving the head projecting, as shown in Figs. 4 and 5. A transverse mortise b, large enough to allow the pin or screw-head C to pass freely through it, is cut in the shank of the hook at the lower part of its ring, so that by turning the hook upward 90 it will slide on the rod over the pin through the mortise. When the hook is dropped to its perpendicular position, it is held to place by the pins C, and prevented from working or slipping on the rod, and so narrowing or 95 closing the mouth of the bag.

Having thus shown the nature and construc-

tion of my improvements, I claim as my invention and desire to secure by Letters Patent—

1. In a postal-bag rack, the combination of 5 a movable section or sections opening either way, with the fixed rack-sections x x , substantially as and for the purposes set forth.
2. The combination, in a movable rack-section, of the platform A, casters a a , elliptic hinge-eye d , pivot e , cam f , and block g , substantially as shown, for the purpose specified.
3. The combination, in a postal-bag rack,

of the hook B, having a mortise, b , in its shank, and ring, with the pins or pegs C in the rack-rod y , substantially as shown, for the purpose 15 specified.

4. The hook B, having in its ring and shank the transverse mortise b , substantially as shown, for the purpose specified.

CHARLES R. HARRISON.
